UNITED STATES PATENT OFFICE.

MARSHALL T. DAVIDSON, OF BROOKLYN, NEW YORK.

IMPROVEMENT IN SECTIONAL STEAM-GENERATORS.

Specification forming part of Letters Patent No. **138,866**, dated May 13, 1873; application filed October 22, 1872.

To all whom it may concern:

Be it known that I, MARSHALL T. DAVIDSON, of the city of Brooklyn, county of Kings and State of New York, have invented a new and Improved Steam-Generator; and that the following is a full, clear, and exact description thereof, reference being had to the accompanying drawing and to the letters of reference marked thereon making a part of this specification.

This invention is in the nature of an improvement in steam-generators; and the invention consists in a steam-generator formed of wrought-iron water-tubes, the rear ends of which are coupled together by return-bends, and the front ends secured to and opening into cast-iron corrugated steam-chambers, and so arranged that the flames and products of combustion will not only pass through the spaces between the several tubes, but will also pass entirely around the whole generator, in the manner hereinafter particularly described.

My boiler is of that kind known as a tubular sectional boiler—that is, a boiler composed of a series of tubes, within which the water is boiled and the steam generated.

In the accompanying drawing, Figure 1 represents a side view of my boiler and setting, and Fig. 2 a front-end view of same.

Similar letters of reference indicate like parts in the several figures.

A represents the tubes composing the boiler. The rear ends of said tubes are coupled together by cast-iron return-bends B, and the tubes are so arranged that as they are placed one above another one pair of tubes will be directly over the space between the lower or under pair of tubes; in other words, the tubes will be what is technically known as "staggered" so that the flames, &c., can freely circulate between and around said tubes, thereby exposing every part of their surface to the action of the heat. The front end of the tubes so arranged are screwed into cast-iron steam-chambers E, each vertical row of double tubes having a separate uptake. These steam-chambers are cast in an irregular form or with corrugations (see Fig. 2) to receive the ends of

the tubes in parallel oblique planes, the several steam-chambers receiving the ends of the tubes of the boiler from the front of the boiler, and by suitable connections F discharge their steam into a common steam-drum, whence it is led to the engine by pipe G. The lower ends of said steam-chambers are also connected by pipes H to a feed-drum, I. The tubes, as before stated, are secured to said steam-chamber and also to the return-bends B by having right-hand screw-threads cut on one end of said tubes, and left-hand screw-threads cut on the other so that, as will be readily seen, to remove one of said tubes it is simply necessary to grasp it with ordinary pipe-tongs and unscrew it from the steam-chamber and the return-bend by the same motion, in the same way replacing the tube removed by a new one. By this means it is obvious that a tube can be removed and a new one replaced with but little trouble and loss of time.

My boiler, being constructed substantially as above described, is set within a brick chamber, K, in such manner that the heat, &c., from the fire will pass through and around the tubes, return-bends, and steam-chambers, as shown by the arrows in Fig. 1.

As will be readily seen, the connections of my tubes, being independent of any rigidly-fixed or unyielding masses of metal, bolts, or tie-rods, have ample opportunity of expanding and contracting without the possibility of strain or causing rupture or leak.

The steam-drum and the feed-water drum are placed in the flue, as shown in Fig. 1, so that a uniform temperature of steam and water is maintained, and nearly all loss from condensation saved.

Having thus described my invention, what I claim as new, and desire to secure by Letters Patent, is—

1. A water-tube boiler having the rear ends of the tubes coupled together in independent pairs by cast-iron return-bends B, and the front ends of said tubes inserted into a corrugated steam-chamber, substantially as described.

2. The arrangement of the several pairs of

tubes having the return-bends and steam-chambers with relation to each other and to the fire-space, substantially as and for the purpose set forth.

3. The combination of independent corrugated steam or water chamber and cast-iron return-bends with water-tubes having right-

and-left-hand screw-threads formed on the ends thereof, for the purpose described.

MARSHALL T. DAVIDSON.
